UNITED STATES PATENT OFFICE.

FRANK L. CONE, OF WINDSOR, VERMONT, ASSIGNOR, BY MESNE ASSIGNMENTS, TO THE NATIONAL-ACME COMPANY, OF CLEVELAND, OHIO, A CORPORATION OF OHIO.

MULTIPLE-SPINDLE METAL-WORKING MACHINE.

1,224,714.

Specification of Letters Patent.

Patented May 1, 1917.

Application filed December 20, 1915. Serial No. 67,853.

To all whom it may concern:

Be it known that I, FRANK L. CONE, a citizen of the United States, residing at Windsor, in the county of Windsor and State of Vermont, have invented new and useful Improvements in Multiple-Spindle Metal-Working Machines, of which the following is a specification.

This invention has relation to automatic multiple-spindle metal-working machines in which the bars from which the finished piece of work are produced are supported in spindles arranged in a turret and are operated on simultaneously and successively by tools mounted on a tool slide.

The object of the present invention is to provide certain improvements in machines of this class, which are illustrated upon the accompanying drawing, described in the following specification and pointed out in the appended claims.

On the accompanying drawings:

Figure 1 shows in plan view a machine embodying my invention.

Fig. 2 represents a front elevation of the same.

Fig. 3 represents a rear elevation of the machine.

Fig. 4 represents an elevation of one end of the machine.

Fig. 5 represents an elevation of the other end of the same.

Fig. 6 represents an enlarged section on the line 6—6 of Fig. 2.

Fig. 7 is a plan view of the middle portion of the machine, showing the supplemental tool slides which are shown in Fig. 6.

Fig. 8 represents a partial side elevation, with the casing in section, of the power-transmitting mechanism for imparting power to the spindle-rotating shaft and to the feed or main drum shaft.

Fig. 9 represents a vertical section through the mechanism illustrated by Fig. 8, some of the parts being removed for the purpose of clearness, and illustrates the sprocket gearing for imparting high speed of rotation to the spindle shaft and also for rotating the pump shaft and the die shaft.

Fig. 10 represents a section on the line 10—10 of Fig. 8.

Fig. 11 is a detail view illustrating the worm shaft which drives the main feed or

cam drum shaft, and the immediately associated parts by which it is driven at different speeds.

Figs. 12 and 12^a (on the same sheet as Fig. 8) show the mechanism for throwing the worm shaft out of operation so that it may be turned by hand.

Fig. 13 represents a section on the line 13—13 of Fig. 8.

Figs. 14 and 15 are sectional views illustrating the roll clutch which is used in imparting slow speed to the worm shaft.

Fig. 16 is a detail view showing, partially in section, the manually operative mechanism for operating the chucks of the work spindles when they arrive at the proper stations, to permit the manual insertion of a fresh bar after one has become exhausted.

Fig. 17 (on the same sheet as Fig. 7) is a detail view, partly in section, illustrating the mechanism for indexing and locking the turret.

Fig. 18 represents a portion of the machine in side elevation, and illustrates in addition to other elements the mechanism for clamping the turret automatically.

Fig. 19 shows the same in end elevation, parts which would otherwise be seen being omitted for the purpose of clearness.

Fig. 20 illustrates the turret-locking mechanism.

Figs. 21 to 27 inclusive illustrate improved mechanism for indexing or rotating the turret with a step by step movement.

Figs. 28 to 31 inclusive illustrate in detail mechanism for imparting a sliding movement to the tool slide.

Fig. 32 is a rear elevation of the machine, partly in section, and illustrates more particularly mechanism for operating the stock stop.

Fig. 33 is an end view of the stock-stop operating mechanism and also illustrates the individual stops for controlling the extent of movement of the supplemental tool slides.

Fig. 34 illustrates the stock stop and the gear and segment by which it is directly actuated.

Fig. 35 is a front elevation of one end of the machine, partly in section, and illustrates the mechanism for opening and closing the "spindle chucks" manually.

Fig. 36 illustrates the connections by

which I secure a forced feed lubrication of the spindles and turret bearing, being more or less diagrammatic and partly in section.

5 Figs. 37 to 42 illustrate the stock stop as being utilized for an additional tool.

Fig. 43 represents a development of the cam for feeding the tool-carrying stock stop.

10 The machine which I have selected for illustration as embodying my invention is particularly adapted for heavy work, such for instance as for use on stock of three inches (and over) in diameter, and is in many respects similar to the machine illustrated and described in U. S. Letters Patent 15 to George Otis Gridley 904,866 dated November 24, 1908. Like the machine illustrated in said Letters Patent, it is provided with a turret adapted to be rotated with a 20 step by step movement and carrying work spindles to which power is imparted through a shaft extending axially of the turret. The tool slide, which is adapted to receive and support one or more tools for each spindle, is 25 mounted upon an extension of the turret which may be formed integral therewith or secured thereto. The tool slide is reciprocated by mechanism including a cam on a main cam or feed shaft, said shaft being rotated at slow speed while the tools are working, and being rotated at high speed during the idle movements of the tools. The stock feed is controlled by the main or cam shaft, as are the turret-indexing and locking mechanisms, and the clutch-operating levers 30 which control the variable speed mechanism for imparting slow and high speeds of rotation to the main feed or cam shaft.

35 The improvements which I shall subsequently describe in detail comprise, among others, an improved and simplified mechanism for rotating the main feed or cam shaft at different speeds and for imparting power to the work spindles, improved mechanism for feeding the main tool slide, improved mechanism for indexing the turret so as to reduce the power required to move the turret, improved mechanism for clamping the turret, in addition to locking it, 40 after it has been rotated, improved mechanism for mounting and operating the tool slides upon which may be mounted forming, cutting-off and other cutters, improved mechanism under manual control for disconnecting or throwing out of action the 45 main feed or cam shaft, improved mechanism for operating a stock stop, a stock stop carrier which may be utilized for carrying a cutter and means for operating the same 50 independently of the tools on the main tool slide, means for collecting and inclosing portions of the operative mechanism in separate casings which may be removed as a unit from the bed and utilized for machines 55 of different sizes, means for mounting the

change gears in such way that they may be normally inclosed in a casing and be removed or withdrawn with a portion of the casing on which they are supported to permit them to be easily changed or to have 60 others substituted therefor, and mechanism for securing a forced feed lubrication of the spindle bearings. In addition to the foregoing, there are various other improvements 65 in the machine illustrated upon the drawing, all of which are fully explained in the following specification.

70 It will be understood, of course, that many of the improvements to which I have thus referred may be utilized in other forms of 75 metal-working machines and that their use is not limited to a machine of the Gridley multi-spindle type. It will be further understood that the improvements are capable 80 of other embodiments and that many 85 changes may be made in the various features of construction, and arrangement and modes of operation, which I will describe, without departing from the scope and spirit 90 of the invention as defined in the claims. 95 Persons skilled in the art will appreciate that the drawings are more or less conventional, particularly those showing the cams for operating the various parts of the machine, and further that the phraseology which I employ is for the purpose of description and not of limitation.

99 Referring to the drawings, it will be seen that the machine is provided with a cabinet base 50, upon which rests a bed or main frame formed of separable portions bolted thereto and secured to each other. The bed comprises at one end the casting 51 forming the head frame in which is journaled the turret for the tool spindles and on which are 105 mounted the supplemental tool slides, and at the other end a casting or tail frame 52 in which is contained the gearing for rotating the spindle-driving shaft and the variable speed gear for actuating the main 110 feed or cam shaft and the mechanism for operating the tool slide. At their upper ends the two frames or castings are rigidly connected and braced by a table 65 bolted thereto. I will subsequently explain the 115 construction of the cabinet base 50 more in detail, in connection with the forced feed lubrication.

120 The turret, which is indicated at 53, is substantially the same as that illustrated in the Letters Patent to Gridley to which I have previously referred, and it consists of a hub provided with peripheral flanges at 125 its ends which are journaled in bearings 54 afforded by a portion of the frame or casting 51. In this turret are the spindles 55 which are rotated by mechanism including a spindle-driving shaft 56 having on its left end a gear 57 intermeshing with gears 58 located on what may be called the rear ends 130

of the spindles, as shown in Figs. 2, 28 and 35. The turret is formed or provided with an axial extension 59 which is cylindrical and which at its end is journaled in a bearing 60 afforded by the frame 52 of the bed.

The tool slide is indicated at 61 and is mounted to slide upon the turret extension 59 toward and from the turret. In cross section it is approximately square, and upon its oblong faces may be secured any suitable forms of tools or cutters. Like the tool slide in the Gridley machine referred to, it is less in diameter than a circle including the axes of the work spindles, so that the 10 end of the tool slide may be carried toward the turret beyond the projecting ends of the work bars and thus permit of the employment of box tools. Rigidly formed on or secured to the outer end of the tool slide 15 there is a block 62 having an arm 63 the end of which is bifurcated to embrace a stationary guideway 64 which is secured to and depends from the table 65.

The turret is indexed, the tool slide fed 20 and retracted and the various operating instrumentalities of the machine are controlled, by a main feed or drum shaft indicated at 66 which extends longitudinally of the bed and which is arranged in the rear 25 portion thereof, as shown in Figs. 4, 6 and 10.

Spindle-driving mechanism.

The power-transmitting mechanism for 30 driving the spindle shaft 56 which extends from one frame 51 to the other frame 52, is located in the frame 52; and for following this description of the same, reference may be had particularly to Figs. 2, 5, and 8 to 15 inclusive. On the top of the frame 52 there is mounted or secured a removable casing 67 in which is mounted a constant-speed prime power shaft 68 which may be driven by an independent motor or which may be provided with a pulley 69 to receive power transmitted by a belt from a countershaft. As shown in Figs. 8 and 10, the drive shaft 68 is provided with a gear 70 which intermeshes with and drives an idler gear 71 mounted on a stud shaft 72 secured in the frame 52. Through the idler gear 71 power is imparted to a gear 73 on a shaft 74 mounted in a bearing 75. On the outer end of said shaft 74 there is a change gear 76 intermeshing with another change gear 77 on the end of the spindle-driving shaft 56. By removing the detachable end wall 78 of the frame 52 the change gear 76 and 77 may be removed and others substituted therefor 50 so as to drive the spindle-driving shaft at either a higher or lower speed. By the simple train of gearing which I have provided, the work spindles and the spindle-driving shaft 56 may be driven at constant 55 speed from the constant-speed drive shaft

68. I find it advantageous to dispense with the employment of manually controlled variable-speed power transmitting mechanism for driving the spindle shaft, as it greatly simplifies the gearing.

70

Mechanism for driving the main feed or cam shaft.

As has been previously stated, it is desirable to drive the fed or cam shaft at slow speed during the working movement of the tools, and at high speed during the idle movements of the tools. Furthermore, it is desirable also that the speed of the cam shaft should be correlated to the speed of rotation of the spindles during the working movements of the tools. As shown in Figs. 9 and 10 the feed shaft 66 is provided with a worm wheel 79 which intermeshes with and is driven by a worm 80 on a cross shaft 81. This cross shaft extends from front to rear of the frame 52 and is mounted in bearings indicated at 82 and 83. At the front end the shaft projects sufficiently so that it may be engaged by a crank handle 84 and thereby be manually operated. Mounted loosely on the cross or worm shaft 81 as shown in Fig. 11 there is a bevel gear 841 which may be clutched thereto by a friction clutch 85, the automatic operation of which will be subsequently described. The bevel gear 841 is driven at high speed by a complementary gear 86 located on a shaft 87 mounted in a bearing 88 in the interior of the frame 52. On the shaft 87 there is a sprocket wheel 89 connected with a sprocket wheel 90 on the constant-speed drive shaft 68 by sprocket chain 91. When the bevel gear 841 is clutched to the worm shaft 81, said shaft will be driven at high speed directly from the constant-speed drive shaft.

75

For driving the cross or worm shaft 81 at slow speed I employ a pick-up clutch having connected therewith a worm wheel 92, as shown in Figs. 11, 14 and 15. This worm wheel is engaged and driven by a worm 93 on a shaft 94 which carries a gear 95 to which power is imparted by a train of reducing gears from the spindle-driving shaft 56.

80

Returning to the worm wheel 92, it will be seen that it is pinned to a clutch member 96 which is loose upon the shaft 81. (See Figs. 14 and 15.) Within the member 96 there is a notched clutch member 97 in the notches of which are placed the spring-pressed clutch rolls 98. When the shaft 81 is driven at high speed it will rotate independently of the clutch member 96, carrying with it the member 97 which is keyed thereon. When the bevel wheel 84 is unclutched from the shaft 81 the clutch member 96 will pick up the clutch member 97 and thus drive the worm shaft 81 at slow

speed. Any other form of pick-up clutch mechanism may be utilized in lieu of the one shown. The friction clutch 85 is moved back and forth automatically by a yoked lever 99 which is secured to a rock-shaft 144 and which is connected by a link 100 with a depending lever 101, the latter carrying a roll 102 which is operated by cams 103 on a cam drum 104 secured upon the main feed shaft 66 and located within the frame 52. The rock-shaft 144 may be operated manually by a hand lever 145 located at the inner end of the frame 52. See Figs. 2 and 10. The outer end wall of the frame is provided with cover plates 105 which may be removed to expose the cam drum and the cams. These cover plates serve another function, as will be subsequently explained. The cam drum 104, as shown in Fig. 32, is hollow and is rigidly secured upon a hub 106 keyed to the main feed shaft 66 and also having pinned thereto the worm wheel 79. Returning now to the train of reducing gearing for actuating the gear 95 and the worm 93 which engages the worm wheel 92 on the cross shaft 81, reference may be had more particularly to Figs. 8 and 10. The said gear wheel 95 intermeshes with and is driven by a gear 107, the shaft 108 of which has on its end a coupling slot 109 to receive a tongue formed on or secured to an idler change gear 110. This gear 110 is one of a train of change gears all of which are supported by a hinged door 111, which is shown in Fig. 5 and which is hinged to the end of the frame 52. There are four stud shafts 112, 113, 114 and 115, all projecting inwardly from the door 111. The shaft 112 affords a bearing for the gear 110. On the shaft 113 are two change gears, 116, which intermesh with the gear 110, and 117 intermeshing with the gear 118 on shaft 114. Secured to the said gear 118 there is a smaller gear 119 intermeshing with an idler gear 120 on the shaft 115. On opening the door 111 the gear 110 is disengaged from the shaft 108 and the change gears are all exposed outside of the frame or casing where they may be replaced by others, or else be arranged in different relation. The gear 120 intermeshes with a gear 121 mounted on a stud shaft 122 and having formed therewith or secured thereto a gear 123 meshing with the gear 124 on the stud shaft 125. Fast with the gear 124 there is a gear 126 intermeshing with and driven by a gear 127 fast upon the spindle-driving shaft 56. From this description it will be apparent that through the reducing train of gears including the change gears, the cross or worm shaft 81 will be driven at low speed when the friction clutch 85 is operated to disconnect the bevel gear 84 from said shaft 81. The number of gears in this train is unimportant, and any other arrangement of

gears may be utilized which is found convenient. In this connection I may note the fact that the gearing is all convenient of access, the frame or casing being provided on its protuberant front side with a large opening 128 which is normally closed by a removable door 129 held in place by a spring latch 130 which may be moved to inactive condition by a cam or eccentric 131 having a knob by which it may be rotated. I have dispensed with the employment of variable speed power-transmitting mechanism under the control of the operator for driving the feed shaft at different slow or working speeds, thereby preventing a lazy operator from slowing down the machine, and depend on change gears for securing such variation as may be needed.

I have stated that the main feed or cam shaft 66 and the cross worm shaft 81 may be disconnected from the power-transmitting mechanism. This is accomplished by a very simple device. The short shaft 94 which has thereon the gear wheel 95 and the worm 93, as shown in Figs. 11 and 12, is journaled in a sleeve 133 pivoted upon a stud 134 projecting inwardly from one of the walls of the frame 52. On the outer end of the shaft 94 there is a sleeve or collar 135 connected by a link 136 with a bell-crank lever 137. The horizontal arm of this lever projects through an aperture in a removable door or closure which is normally affixed to one end of the casing or frame 52, and the bell-crank lever is pivoted upon a stud 139 supported by said closure 138. The vertical arm 140 of the lever is formed as a handle by which the lever may be manually moved about the pivot 139 so as to force the worm 93 into and out of engagement with the worm wheel 92. This handle may be provided with any suitable locking mechanism by which it may be held in position to maintain the worm in engagement with the worm wheel. As illustrated the hub of the lever carries a spring-pressed pin 141 adapted to snap into a socket in the bearing lug to hold the arm in its normal position. This spring-pressed pin may be moved out of its socket by a spring-pressed pin 142 inserted in the handle and having its lower end beveled so as to pass through a slot in the pin 141. When the worm 93 is disengaged from the wheel 92 it is also desirable to throw out the high speed clutch 85, and hence the shaft 144 to which the lever 99 is secured may be rocked by the hand lever 145 which, as previously stated, is located on the left end of the frame or casing 52, as shown in Fig. 2. The operator, after having disconnected the slow-speed worm from the cross worm shaft 81 and after moving the clutch 85 to its inactive position, is able to rotate the main feed or cam shaft by the handle 84 applied to the projecting end of the said shaft 81.

At other times the speed of rotation of the said cam shaft 66 is controlled by the cams thereon which move the friction clutch 85 into active or inactive position.

5 *Feeding mechanism for tool slide.*

The tool slide, as stated, travels back and forth upon the turret extension, and has secured thereto the block 62. Secured to or

10 formed on said block there is a lug 150, as shown in Fig. 30, to which there is secured a bar 151 which projects through the inner end wall of the frame or casing 52. This bar has rigidly secured to it the hub of a

15 block 153 formed with an arm 154 provided with a stud having a roll 155 thereon to be engaged by a cam located on the periphery of the cam drum 104. The collar 153 has another arm 156 arranged to slide upon a

20 guide bar 157 affixed at its ends in the end walls of the frame or casing 52. The arm 154 of the collar 153 has a roll 158 journaled on a stud projecting from the end thereof and resting upon a hardened steel guide bar 25 159 secured in a holder 160 placed within the casing or frame 52. By thus guiding the end of the pusher bar 151 upon the two guides or guideways 157, 159, I am able to prevent any springing of the pusher bar.

30 This is an important consideration when it is recognized that there are frequently located upon the tool slide drilling and boring tools which encounter serious resistance in the performance of their operations, particularly in machines operating on large stock. This mechanism which I have described is practically all located within the frame or casing 52. The two guides 157 and 159 are on opposite sides of the plane

35 of the axis of the roller 155 and the pusher bar 151, as shown in Fig. 29, and hence it is impossible for the cams on the drum 104 either to twist the pusher bar 151 or the collar block 153 thereon. The greater portion

40 of the lateral thrust of the cam on the roll 155 is resisted directly by the roll 158 and the guideway 159 which are in the direct line of the thrust. The two guide bars or guideways 157 and 159 are supported at

45 both ends by solid portions of the bed frame 52 in one of which the turret extension 59 is journaled.

Turret indexing and locking mechanism.

50 The mechanisms for indexing and locking the turret are best shown in Figs. 20 to 27 inclusive and Figs. 33 and 34. The locking mechanism for the turret does not differ materially from that illustrated in the Letters Patent to Gridley which have been previously mentioned herein. It is shown in Fig. 20, and consists of a spring-pressed locking bolt 161 mounted to slide in a bearing in the frame 51 and arranged to engage

55 hardened steel socket pieces 162 placed in

one of the peripheral flanges of the turret. The locking bolt is forced into position by a spring 163 placed in a cap 164 secured to the rear wall of the frame 51. For the purpose of moving the locking bolt outward 70 against the tension of the spring, I employ a bell-crank lever 165, one arm of which is engaged with the locking pin, and the other arm of which has a roll 166 adapted to be engaged by a cam 167 on a drum 168 secured to the main feed or cam shaft 66. This mechanism is shown in rear elevation 75 in Fig. 3.

After the locking bolt is withdrawn, the turret is rotated through an arc of ninety 80 degrees by mechanism operating on the principle of the Geneva stop. On the inner face of one of the flanges of the turret there are placed four pairs of short guide bars 171, the guideways afforded thereby being radial of 85 the turret. A revolving bar 169 is provided with a roll 170 adapted to enter the guideways successively and by each revolution to turn the turret through an arc of ninety degrees. Instead of having this revolving arm 90 fixed with reference to its center of rotation, it is adapted to move transversely thereof so that after it has once started to rotate the turret its leverage thereon will remain practically constant until the turret has reached 95 nearly the end of its ninety degrees of rotation. To accomplish this purpose the bar 169 is mounted upon the drum 168 which carries the cam 167 for operating the locking pin. It is provided with a longitudinal 100 slot to receive said shaft and to permit it to move relatively thereto. The sides of the bar are guided by rolls 172 supported upon the studs 174 projecting from the face of the cam drum 168, and it is held against the 105 face of the drum by cross bars 173 secured to said studs 174. From this description it will be seen that as the cam drum 168 rotates, the bar 169 will be caused to revolve with it. The movement of the bar longitudinally of its length is controlled by a fixed cam 175 rigidly secured to a wall of the frame or casing 51. This cam 175 has a cam groove 176 of approximately the shape shown in Figs. 25, 26 and 27, and into this groove 110 projects a roll 177 mounted upon a stud 178 projecting from the face of the bar 169 near its end.

The operation of the bar will be clearly understood from the illustration in Figs. 25 115 to 27. In Fig. 27 the entire bar has been moved in a direction away from the turret. As it rotates in the direction of the arrow until it reaches the position shown in Fig. 25, it is moved transversely of the feed shaft 120 125 66 practically to its extreme of movement lengthwise. At this moment the roll 170 is entering one of the guideways afforded by a pair of guides 171. Then as the cam shaft continues its rotation, the bar causes the ro- 130

tation of the turret, but as the bar swings about its axis it is also moved longitudinally away from the turret until it reaches a dead center position (*i. e.*, in a line connecting the axes of the turret and the feed or cam shaft 66) as shown in dotted lines in Fig. 26, and thereafter as it continues its rotation the bar 169 is moved lengthwise toward the turret until the turret has about completed its quarter turn, as shown in Fig. 26. Thereafter as the bar revolves to the position shown in Fig. 27 it is again moved lengthwise so that its roll 170 approaches the shaft 66.

The advantages of this construction will be quite apparent. In the first place it should be remembered that the turret is relatively heavy and that it carries with it the bars of stock which are to be operated upon and which may be of great weight. Where the usual Geneva stop mechanism is employed, as in the Gridley machine, the leverage of the bar or arm upon the turret gradually diminishes as the arm approaches the axis of the turret, and, in heavy machines, unless considerable momentum is imparted to the turret it is apt to stick or cease its rotation when it is moved through an arc of about forty-five degrees, making it necessary to move the turret at relatively high speed so as to secure the required momentum or else to turn it over manually. With my indexing mechanism, however, I secure the advantage of starting the movement of the turret slowly, this being incident to the employment of the Geneva stop mechanism, and at the same time I prevent any substantial variation in the leverage or prevent loss of power by moving the bar or lever lengthwise away from the axis of the turret during the first half of the rotative step of the turret, and then advancing the bar again during the second half of the step until the indexing is nearly completed. This mechanism is all contained within the rear side of the frame or casing 51, whereby it is protected.

In Fig. 3 a removable portion of the frame or casing has been removed to show the mechanism, this removable portion being shown in Figs. 1 and 4 at 180.

Turret-clamping mechanism.

In addition to locking the turret after it has been rotated through an arc of ninety degrees, I also employ improved mechanism for clamping the turret. In this connection reference may be had to Figs. 3, 18, 19, 20 and 21. That portion of the frame 51 which serves as bearings for the turret is split at the top as shown in Figs. 19 and 20, so as to provide substantially split ring bearings for the turret flanges. These split portions may be drawn together firmly to clamp the turret, and for this purpose I employ two clamping

bars 181 which extend horizontally through the top bearing portion of the frame 51 from front to rear as shown in Figs. 18 and 20. On the front projecting end of each bar 181, which is threaded, I put a nut 182. The rear ends of the bars have heads 183 which are slotted to receive the ends of the horizontal wedge bar 184 placed on the exterior of the rear side of the frame 51. This bar 184, as shown in Fig. 21, bears with one edge 70 against the rear face of the adjacent portion of the bearing or frame, and its other edge engages rolls 186 located in slots in the said heads 183. The shape of the bar 184 may be apparent by an inspection of Fig. 7, 80 which shows it in plan view, this figure also showing the splits in the bearings which are indicated at 185, and the rolls 186 in dotted lines. It will be noted by an examination of the last-mentioned figure that when the wedge 85 bar 184 is moved in one direction the split portions of the bearing will be drawn together so as tightly to clamp the turret, and that when the wedge bar is moved in the opposite direction the clamping portions of the bearing will be released so as to permit the turret to turn freely. The wedge bar 184 is automatically moved in one direction or the other by means of a two-armed lever 187 fulcrumed on the stud 188 mounted in the lugs 90 189 and extending downwardly through an aperture in the top portion of the frame 51. The upwardly extending arm of the lever is connected to a stud 190 projecting from a block 191 secured to the wedge bar 184. The 100 depending arm of the lever is provided with a roll 192 adapted to be engaged by a cam 193 on the cam drum 168 which has been previously described as operating the index mechanism and the locking pin for the turret. The parts are so timed that as the locking pin is withdrawn the cam 193 operates the lever 187 so as to move the wedge bar 184 in position to unclamp the turret, and thereupon the indexing mechanism operates 105 110 to advance the turret one step in its rotation. At the same time that the locking pin enters and locks the turret, the wedge bar is operated to clamp the turret in its bearings. Thus all three of these operating mechanisms are controlled by a single cam drum on the main feed or cam shaft 66. These parts, however, are not actuated until the tool slide has been moved far enough away from the turret to clear the tools from the work, and their operation takes place while the cam shaft 56 is rotating at high speed.

Stock-feeding mechanism.

It is unnecessary to describe in detail the 125 stock-feeding mechanism, as it does not differ materially from that shown in the Letters Patent to Gridley previously mentioned. I have added, however, an additional feature, which may be referred to, by means of 130

which each spindle chuck, after it has reached the proper station for the feeding of the stock therethrough, may be operated by hand to permit the insertion of a fresh bar.

5 It will be remembered that each spindle is provided with a chuck-operating sleeve or collar such as indicated at 200 in Fig. 35. I provide means for moving each of these collars as its spindle arrives at the stock-feeding station. To this end I mount in guideways or apertures formed in the end walls of the frame 51 a bar 201 having rack teeth 202 engaged with a gear segment 203. This segment is formed on or secured to a sleeve 204 which also carries a weight 205 which tends to swing the segment to the left. The sleeve is keyed upon a bar 206 projecting forwardly through the front wall of the frame 51, as shown in Figs. 2 and 4, and 10 on its forwardly projecting end it is provided with a long handle 207 by which it may be manually rocked. On the projecting end of the bar 201 there is a collar 208 provided with a flange 209 to enter the groove 210 of each collar or sleeve 200 as the spindle reaches the stock delivery station in its rotation with the turret. By the means described the operator can operate the spindle chuck so as to release the stock bar held 15 therein, and may insert a fresh bar, after which the handle 207 may be operated in the other direction to return the chuck to its original condition so as firmly to clamp a fresh bar of stock.

55 *Supplemental tool slides.*

The machine is provided with two supplemental tool slides which may be utilized for carrying forming, cutting-off and other varieties of tools for operating upon the work. In the following description I shall refer more particularly to Figs. 6, 7, 32 and 33. The two slides are indicated respectively at 220 and 221, and they are gibbed to slide on brackets 222, 223 which are preferably cast integral with the frame 51 to insure their rigidity. The two slides are cam fed independently of each other, transversely of the longitudinal lines of 45 the bed and of the spindles. For this purpose I place beneath them a cross shaft 224 to which is secured a bevel gear 225 intermeshing with and driven by a complementary bevel gear 226 on a shaft 227 arranged in 50 parallelism with the main feed shaft 66 and geared thereto by two gears 228 and 229 which are of the ratio of one to one. These gears 228, 229 can be seen in Fig. 18, and they are located within the frame 55 51. Keyed upon the opposite ends of the cross shaft 224 there are the two cam drums 230 and 231. In a recess provided in the under side of each of said tool slides there is a nut 232 engaged by a screw bar 233 60 which is journaled in the slide and held

against longitudinal movement by the head 234 thereon and by collar 235 pinned thereto. Each nut is preferably rectangular in cross section, and the guideway in which it moves is similarly formed. Each nut is provided 70 with a downwardly extending stud 236 carrying a roll 237. The rolls of the slides 220 and 221 are engaged by cams mounted upon the two drums 230, 231. These cams are conventionally illustrated at 238 and 239. 75 Each slide is relatively quite broad, as shown for example in Fig. 7, and is provided with undercut grooves 240 for the reception of such cutters in such desired locations as may be used in connection therewith. For limiting the inward movement of the two slides I provide a stop mechanism by which the movement of the slide is independently controlled for each spindle. Upon the upper surfaces of the 80 two slides are affixed the two brackets 241, 242 carrying the two horizontal oppositely projecting adjustable abutment screws 243, 244. These screws are in a plane just below the horizontal plane of the axis of rotation 85 of the turret, as shown in Fig. 6. The turret is provided in its periphery with four sets of adjustable screws or stops, one set of four for coöperation with the abutment screw 243, and the other set for coaction 90 with the screw 244. The screws of the first-mentioned set are indicated at 245 and those of the second-mentioned set at 246. These stops 245 and 246 are adjustable and 95 may be secured after adjustment by set screws 247. Thus as each spindle during the step by step rotation of the turret is brought to a position where it may be acted upon by cutters located on one or the other of the two slides, a stop individual to that spindle is brought into position to be engaged by the coacting abutment on said slide. In this way I insure that the cutter shall be pressed home and that the particular piece of work held by the spindle shall be operated on with accuracy. 100

105 *Stock stop.*

I have provided, as I have stated previously, an improved stock stop and mechanism for operating it, and as I shall subsequently explain, I may use the same carrier which supports the stop for the purpose of supporting an additional tool which may be reciprocated independently of the main 115 tool slide and the supplemental cross slide or tool holder. Where the stock stop is employed only for the purpose of limiting the movement of the stock, I prefer that it shall be normally in an inactive position so 120 as not to interfere with the operation of the main tool slide, and that it shall be automatically advanced and rocked into registration with the advancing bar, as it is being fed through the spindle, so as to 125 130

stop the feeding movement thereof when the bar has been advanced to the proper extent. To this end the stock stop has both an axial and a swinging or rocking movement, both movements being controlled by the main feed or cam shaft 66.

Referring now to Figs. 32 and 33, the stock stop consists of an adjustable abutment screw 250 mounted in a carrier 251 which is in the form of a swinging arm or lever. Said lever is formed with and projects from a sleeve 252 which is splined upon another sleeve 253 located upon the enlarged end portion of the cam or feed shaft 66. This end of the feed shaft is hollow for the reception of a sliding bar 254 which is provided with a cross pin 255 projecting through a longitudinal slot 256 in the hollow end of the shaft 66. The ends 20 of the pin extend into a groove in the interior of the sleeve 252, this groove being formed by an internal rib 257 and by a ring 258 screwed into the end of the sleeve. When the bar 254 is reciprocated it carries 25 with it the sleeve 252 and consequently the arm or carrier 251. The bar 254 is reciprocated by an internal cam located within the hollow drum 104 which, as will be remembered, is rigidly secured to the worm 79 30 on the cam shaft 66.

Mounted loosely on the end of the bar 254 there is a hub 259 having an arm 260. This hub is held against axial movement on the bar by collars 261, 262. The arm is 25 provided with two rolls at the end thereof, one at 263 by which it is guided during the reciprocation of the bar, and the other 264 which is engaged by the internal cams in the drum 104. For guiding the hub 259 40 and the arm 260 the movable closure or cover plate 105, which, it will be remembered, is secured to the end wall of the frame 52, is provided with a reentrant portion 265 having a semi-circular groove to 45 receive the hub 259, as clearly indicated in Fig. 32. The said cover plate or closure is also provided with two internal separated parallel projections 266 forming a guide-way to receive the roll 263. From this construction it will be apparent that as the drum 104 rotates, the internal cams, of which one is indicated at 267, by engagement with the roll 264 will move the bar 254 axially 50 first in one direction and then in the other. 55 This provides for the movement of the stock stop axially.

To secure the rocking movement of the stock stop on its carrier 251 I provide the mechanism which is best shown in Figs. 33 60 and 34. In these two figures it will be noted that there is formed on or secured to the sleeve 253 a gear 268 which intermeshes with and is operated by a gear segment 269 secured upon a shaft 270. Also secured to said shaft 270 there is an arm or lever 271 carry-

ing on its end a roll 272 extending into a cam groove 273 in a cam disk 274 keyed upon the feed or cam shaft 66. As the cam disk rotates, the arm 271 is swung about the axis of the shaft 270 carrying with it the segment 269 which by reason of its engagement with the gear 268 rocks the carrier 251 about its axis from its normal inactive position shown in Fig. 34 to its active position in alignment with one of the spindles as shown 70 in Fig. 33. These parts are all so timed that the stock stop is first moved lengthwise of its axis of movement the proper distance and then swung about its axis into alignment with the stock, and after the stock has been 80 fed, the stop is then swung about its axis and returned by an axial movement to its original starting point. It is quite apparent that the extent of axial movement of the stop depends upon the character of the cams 85 that are mounted on the interior of the drum 104, that, of course, these cams may be of any suitable form and pitch, and that several sets may be supplied so as to be used for the production of pieces of work of different 90 lengths. The cam disk and the gear and segment and a portion of the sleeve 252 are all inclosed within a removable casing 275 removably secured to the inner end wall of the frame 52. 95

In Figs. 37 to 42 I have illustrated how the carrier 251 for the stock stop may be utilized for supporting a tool for operation upon the work after the stock bar has been fed. In this case the carrier is provided 100 with a lateral extension 276 in which is mounted a drill 277 or other form of tool for operating on the work. Thus I provide an additional or supplemental tool holder or carrier, which is independent of the main 105 tool slide and also of the transverse tool slides, and which is capable of movement transversely of a work spindle to bring it to working position, and then of movements longitudinal of the spindle. This requires 110 a somewhat different arrangement of cams in the drum 104 and also requires a differently shaped groove 273 in the cam disk 274, so that the carrier 274 will be operated substantially as follows: Assuming that the turret 115 has just been indexed and locked, then the bar 254 is moved toward the turret the proper distance and the sleeve or hub 252 is rocked far enough to bring the stock stop in alignment with the spindle through which 120 the stock is to be fed. The carrier 251 then remains stationary a short time until the stock bar has been fed and the stock bar clamped in the spindle chuck. Then the carrier 251 is rocked reversely and is withdrawn axially, far enough to bring the end of the tool carried thereby clear of the end of the stock. Then the carrier is rocked far enough in a direction toward the spindle axis to bring the tool into potential work- 125

ing position, and while it is held in this angular position the bar 254 is advanced toward the turret to cause the tool to act on the work, and after the cutting or drilling operation is completed the bar 254 and the carrier 251 are retracted, after which the carrier is rocked in a direction away from the spindle axis to return the carrier in an inactive position, out of the way. When the carrier is being employed as a tool holder, I may dispense with a tool on the main tool slide for operating on the work held by the spindle in the fourth or stock-feeding position.

15 In Fig. 43 I have shown a development of the length-feeding cams 264 in the interior of the drum, and have illustrated graphically the lateral movements of the carrier in their timed relation to the longitudinal or axial movements thereof, when the carrier is utilized for holding both the stock stop and a supplemental tool. In Fig. 38 I have shown the cam 274 having the cam groove 273 to cause the described lateral or rocking movements of the carrier 251.

20 The parts, as will be seen, are all compactly arranged, the feed shaft 66, the bar 254, and hollow shaft comprising the hub 252 and sleeve 253, all telescoping.

25

Forced feed lubrication.

One of the highly desirable features of the machine which I have illustrated in the drawings is that lubricating oil is fed by means of a pump to the spindles and turret bearings, and after being used is caught and re-used; thus the oil circulates through the most important bearings of the machine, to wit, the spindle bearings. In Fig. 36 I have shown somewhat diagrammatically and conventionally the mechanism which I employ for this purpose. In connection with the said figure, reference may be had to Fig. 9. It will be recalled that in the explanation of the gearing for driving the feed or cam shaft 66 at high speed, power is transmitted from the constant-speed drive shaft 68 to a shaft 87. It is from this shaft 87 that power is transmitted for operating the pump by which the lubricating oil is supplied to the bearings. The shaft 87, as shown in Figs. 9 and 11, is provided with a sprocket wheel 290 by which power is transmitted through a sprocket chain 291 to a sprocket wheel 292 on a pump-driving shaft 293. This connection is also illustrated in Fig. 36. Said shaft 293 operates the piston of a rotary pump which is indicated conventionally at 294 and which is located in the frame 52 and which is supported by a bracket 295 supported by the bed 50. The interior of the bed is formed to provide a relatively large open central chamber 296 into which may flow from the tools the oil 65 which is used in cutting and which is ordi-

narily supplied to the tools. Then below the frame 51, and hence underneath the turret, the bed is cast to form a tank or receptacle 297 for lubricating oil. This tank 297 is connected by a pipe 298 with a similar tank or receptacle 299 formed in that portion of the bed which is below the frame 52, by a suitable horizontal partition so that oil which drops from the bearings into the receptacle 297 flows into the receptacle 299 and is thence pumped upward by the pump 294 through a filter 300 to a pipe 301. The pipe 301 delivers the oil to a small casing 302 surrounding the spindle-driving shaft 56. This shaft is hollow for a portion of its length and receives oil into its interior through a radial hole 303 leading into the interior of the casing 302. From the shaft the oil is delivered through another radial hole 304 into a cavity 305 formed within the spindle extension 59 which encircles the spindle-driving shaft 56, thus forming an annular conduit for the oil. From said conduit leads a series of ducts 306, 307, there being two ducts for each spindle, one leading to each spindle bearing, as shown in Fig. 36. It is unnecessary to describe these spindles and their bearings in detail, as they are illustrated and described in my copending application, Serial No. 6,877, filed February 8, 1915. Not only is the oil supplied to the spindles, but it may be also supplied to the bearings for the turret through conduits leading through the turret itself.

By the mechanism shown it is quite apparent that I am able to force a steady flow of oil to the spindle bearings and thus remedy one of the most serious faults that has been found to exist in multiple spindle machines. I am able to prevent wear of the bearings and to insure a smoothness of rotation of the spindles which it has been heretofore impossible to obtain. Not only are the spindles lubricated, but also the bearings for the spindle-driving shaft, as will be readily apparent from an inspection of Fig. 36.

The cutting oil which drops into the main portion of the bed flows into a receptacle or tank 308 which is located immediately below the tank 299. It is drawn therefrom through a pipe 309 by a pump 310 having a shaft 311 which is connected by a coupling 312 with the power driven shaft 293. A pipe 313 leading from the pump is provided with branches leading to the various tools, these branches not being shown.

In connection with the turret-indexing mechanism, I neglected to state that in the guideways in the turret formed by the parallel guides 171, I may locate cross pieces 1711 to engage the roll 170 on the arm 169 to assist the high point 1761 in the cam groove in moving the arm or bar 169 longitudinally rearwardly from the turret.

Having thus explained the nature of my

invention and described one form of its embodiment, without describing all the forms in which it may be made or all the modes of its use, what I claim is:

5. 1. A multiple-spindle metal-working machine comprising a bed, a turret journaled therein, a plurality of tool spindles carried by the turret, a tool slide, a plurality of tools disposed on said slide, a cam or feed shaft having a drum thereon, a pusher bar connected to the tool slide, and arranged to be operated by said drum, and guides for the pusher bar arranged on opposite sides thereof to resist the thrust of the drum on 15 said pusher bar.
2. In a multiple-spindle metal-working machine, the combination with a tool slide having a plurality of side faces to receive tools, a central supporting guide therefor, a 20 pusher bar therefor, a cam shaft and a cam thereon for reciprocating said pusher bar, of a guide bar parallel with the pusher bar, and a slide rigid with the pusher bar and movable on said guide bar.
25. 3. In a multiple-spindle metal-working machine, the combination with a tool slide, a guideway therefor passing therethrough, a cam, and a pusher bar for said tool slide, of a member secured to said pusher bar, and having means for engagement with 30 said cam, a guideway parallel to said pusher bar, and a roll on said member movable on said guideway.
4. In a multiple-spindle metal-working 35 machine, the combination with a tool slide, a guideway therefor, a cam, and a pusher bar for said tool slide, of a block secured to the end of said pusher bar, a roll on said block adapted to be engaged by said cam, a guideway parallel to the pusher bar, and a roll on said block movable on said guideway to resist the lateral thrust of the cam on said first-mentioned roll.
5. In a multiple-spindle metal-working 45 machine, the combination with a tool slide, a central supporting guideway therefor, a cam, and a pusher bar for said tool slide, of a block secured to the end of said pusher bar, separated parallel guide bars along- 50 side the pusher bar, means on said block for engaging guide bars with a rolling and a sliding engagement respectively, and means on said block for engagement by said cam.
55. 6. In a multiple-spindle metal-working machine, a bed comprising a hollow frame having end walls, a tool slide, a guideway therefor supported by said bed, a pusher bar for said tool slide extending through 60 one of said end walls into said hollow frame, a feed or cam shaft also extending into said frame, and having a cam drum thereon within said frame and between the end walls thereof, and means on said pusher

bar and located in said frame for engagement by said drum.

7. In a multiple-spindle metal-working machine, a tool slide, a guideway therefor, a pusher bar connected to the tool slide, a feed or cam shaft, a cam drum on said shaft, a hollow bed frame inclosing said drum and the end of said pusher bar, a guide supported by the end walls of said frame, a block on said pusher bar engaged with said guide, and a roll on said block 75 for engagement by the cam drum.

8. In a multiple-spindle metal-working machine, a bed comprising two separated hollow frames, a spindle turret journaled in one of said frames, and having an axially extending portion journaled in the end wall of the other frame, a tool slide between said frames and movable on said axially extending portion, a pusher bar connected to said tool slide and projecting into the second mentioned frame, a cam shaft having a cam drum arranged within said second mentioned frame, and a block within said second mentioned frame and secured to said pusher bar for coöperation with said cam 80 drum.

9. In a multiple-spindle metal-working machine, a bed comprising two separated hollow frames, a spindle turret journaled in one of said frames, and having an axially extending portion journaled in the end wall of the other frame, a tool slide between said frames and movable on said axially extending portion, a pusher bar connected to said tool slide and projecting into the second mentioned frame, a cam shaft having a cam drum arranged within said second mentioned frame, a block within said second mentioned frame and secured to said pusher bar for coöperation with said cam 90 drum, a guide in said last mentioned frame and having its ends supported by the end walls thereof, and means on said block for engaging said guide.

10. In a multiple-spindle metal-working machine, a bed comprising two separated hollow frames, a spindle turret journaled in one of said frames, a tool slide movable between the adjacent ends of said frames, a main feed shaft extending from one of said frames to the other, power-transmitting mechanism in one of said frames for driving said main shaft, and a drum located within said frame for operating said tool slide.

11. In a multiple-spindle metal-working machine, a bed comprising a hollow head frame and a hollow tail frame, a turret journaled in the head frame and provided with a plurality of spindles, a spindle-driving shaft extending from the head frame into the tail frame, a tool slide between said frames, a feed shaft, and power-transmit-

ting mechanism confined within the tail frame for rotating the spindle-driving and the feed shafts.

12. In a multiple-spindle metal-working machine, a bed comprising a hollow head frame and a hollow tail frame, a spindle-carrying turret journaled in the head frame, a spindle-driving shaft extending from the head frame into the tail frame, a tool slide 10 located between said frames, a feed shaft extending into the two frames, a cam drum on said feed shaft and located within the tail frame for operating the tool slide, and power-transmitting mechanism located in 15 the tail frame for rotating the spindle shaft and for imparting high and low speeds of rotation to the feed shaft.
13. In a multiple-spindle metal-working machine, a bed comprising a hollow head frame and a hollow tail frame, a spindle-carrying turret journaled in the head frame and having an axial extension journaled in the tail frame, a tool slide on said axial extension and located between said frames, a 20 pusher bar connected to the tool slide and extending into the tail frame, a feed shaft extending from one frame into the other, a variable speed power-transmitting mechanism confined within the tail frame for 25 operating the feed shaft, and a cam drum confined within the tail frame and located on said feed shaft for operating the pusher bar, and turret-indexing mechanism actuated by said feed shaft and located within 30 the head frame.

14. In a multiple-spindle metal-working machine, a bed comprising a hollow frame, an operative driven shaft located in said frame, a power-transmitting shaft in said 40 frame, a train of power-transmitting change gears between said shafts, a door for said frame, and means for mounting said gears on the inside of said door whereby they are removable therewith.

- 45 15. In a multiple-spindle metal-working machine, a bed comprising a hollow frame, an operative driven shaft located in said frame, a power-transmitting shaft in said frame, a train of power-transmitting change gears between said shafts, a door for said frame, means for mounting said gears on the inside of said door whereby they are removable therewith, and means for hinging said door to said frame.

- 55 16. In a multiple-spindle metal-working machine, a bed comprising a hollow frame, an operative driven shaft located in said frame and having a coupling member on the end thereof, a power-transmitting shaft in 60 said frame, a door hinged to said frame, and a train of change gears for transmitting power from one of said shafts to the other, means for supporting said gears on the said door, and a complementary coupling member

connected with one of said gears for engaging the first mentioned coupling when said door is closed.

65 17. In a multiple-spindle metal-working machine, a main drive shaft, a spindle-driving shaft, a feed shaft, a turret having a plurality of spindles driven by said spindle-driving shaft, a tool slide actuated by said feed shaft, gearing connecting the main shaft with the spindle-driving shaft, sprocket gearing between the main shaft 70 and the feed shaft for driving the latter at high speed independently of the spindle-driving shaft, reducing gearing actuated by the spindle-driving shaft for driving the feed shaft at low speed, and clutch mechanism controlled by the feed shaft for connecting the feed shaft alternately with the sprocket gearing and the reducing gearing.

75 18. In a multiple-spindle metal-working machine, a main drive shaft, a spindle-driving shaft, a feed shaft, a turret having a plurality of spindles driven by said spindle-driving shaft, a tool slide actuated by said feed shaft, gearing connecting the main shaft with the spindle driving shaft, sprocket gearing between the main shaft 80 and the feed shaft for driving the latter at high speed independently of the spindle-driving shaft, reducing gearing actuated by the spindle-driving shaft for driving the feed shaft at low speed, and clutch mechanism controlled by the feed shaft for connecting the feed shaft alternately with the sprocket gearing and the reducing gearing, in combination with a frame inclosing said 85 gearing, and a door on said frame supporting a portion of the reducing gearing which is movable with said door into an inactive position.

90 19. In a metal-working machine, a tool slide, a constant-speed drive shaft, a feed shaft therefor provided with a worm wheel, a cross shaft having a worm in engagement with said worm wheel, a spindle-driving shaft driven by the constant-speed drive 95 shaft, power-transmitting mechanism between said cross worm shaft and said spindle driving shaft, a bevel gear on said feed shaft, a cross shaft having a bevel gear intermeshing with the first mentioned 100 bevel gear, power-transmitting mechanism between the bevel gear cross shaft and the constant-speed drive shaft, and clutch mechanism controlled by the feed shaft for alternately connecting said worm wheel and 105 said first mentioned bevel gear with said feed shaft.

110 20. In a metal-working machine, a tool slide, a feed shaft having a cam drum for operating the tool slide, and power-transmitting connections for driving said feed shaft, comprising a worm wheel, a worm shaft, a pivoted bearing for said worm shaft,

a manually operated lever for swinging said worm shaft about its pivot to move said worm into and out of engagement with said worm wheel, and means for manually 5 operating said feed shaft.

21. In a metal-working machine, a tool slide, a feed shaft having a cam drum for operating the tool slide, and power-transmitting connections for driving said feed 10 shaft, comprising a cross shaft geared to said feed shaft, power-transmitting mechanism including a manually operatable clutch normally controlled by the feed shaft, for driving said cross shaft at high speed, 15 power-transmitting mechanism for driving said cross shaft at low speed and including a pivoted shaft carrying a worm, a worm wheel on the cross shaft, and a manually operated lever for moving said pivoted shaft 20 to engage the worm with or to disengage it from said worm wheel.

22. In a multiple-spindle metal-working machine, the combination with a bed, a main tool slide, a spindle-carrying turret, 25 and a feed shaft, of a cross shaft, a shaft parallel to the feed shaft, gears connecting said shafts, bevel gears connecting said second-mentioned shaft and the cross shaft, supplemental transversely movable tool 30 slides supported by said bed, and separate cam drums on said cross shaft for reciprocating said supplemental tool slides independently of each other.

23. In a metal-working machine, the combination with a spindle-carrying turret, a main tool slide, a feed shaft therefor, and a bed for supporting said elements, of transverse ways on said bed, supplemental tool 35 slides arranged to slide on said ways, a cross shaft supported by said bed and arranged beneath said ways, separate cam drums, one beneath each of said supplemental tool slides, on said cross shaft, for reciprocating said slides independently of each other, a second 40 shaft parallel to and geared to said feed shaft, and bevel gearing connecting said second shaft with said cross shaft at a point intermediate of said drums.

24. In a metal-working machine, a work 45 spindle, a stock-feeding mechanism, a stock stop, arranged to move in a direction parallel with the spindle and to rock about an axis, and mechanism for automatically imparting said movements to said stock stop.

25. In a metal-working machine, a work 50 spindle, a tool slide, a feed shaft, a stock stop normally out of alinement with the spindle, a rock-shaft parallel with the spindle, an arm thereon supporting said stop, 55 and mechanism actuated by the feed shaft for rocking said rock-shaft and for reciprocating it axially.

26. In a metal-working machine, a work 60 spindle, a tool slide, a feed shaft, a stock 65 stop normally out of alinement with the

spindle, mechanism for automatically moving said stock stop in a direction parallel to the spindle to place it in a predetermined plane transverse to the spindle axis, and to withdraw it therefrom, and mechanism for 70 automatically moving said stock stop laterally into alinement with said spindle and retracting it therefrom.

27. In a multiple-spindle metal-working machine, a rotary turret carrying a plurality 75 of work spindles, a tool slide for a plurality of tools, and stock stop mechanism comprising a rock-shaft, an arm thereon, a stock stop on said arm, mechanism for reciprocating said rock-shaft to move said stock to 80 ward and from the turret, and mechanism for rocking said shaft to move said stop into and out of alinement with one of the spindles.

28. In a multiple-spindle metal-working 85 machine, a rotary turret carrying a plurality of work spindles, a tool slide for a plurality of tools, a feed shaft for reciprocating the tool slide, a pivotally mounted stock stop, mechanisms actuated by the feed 90 shaft for rocking said stop about its pivot, and for moving it axially of its pivot.

29. In a multiple-spindle metal-working machine, a rotary turret carrying a plurality of work spindles, a tool slide for a plurality of tools, and stock-stop mechanism 95 comprising a hollow sleeve or rock-shaft, an arm projecting therefrom, a stock-stop on said arm, a shaft telescoping in said sleeve or rock-shaft, and mechanism actuated thereby for rocking said sleeve or rock shaft.

30. In a metal-working machine, the combination with a work spindle, and stock-feeding mechanism, of a stock stop, an oscillatory arm supporting said stop, a gear secured to said arm, a rock-shaft having a segment intermeshing with said gear to rock 105 said arm, and mechanism for automatically rocking said rock-shaft.

31. In a metal-working machine, the combination with a work spindle and a stock-feeding mechanism, of a rotary shaft, an arm mounted to oscillate thereon, a stock stop on said arm arranged to be moved thereby into alinement with said spindle, a gear secured 110 to said arm in axial alinement therewith, a rock-shaft having a segment meshed with said gear, and also having an arm or lever, and a cam fixed on said rotary shaft and engaged with the last mentioned arm or 115 lever for oscillating said rock-shaft.

32. In a metal-working machine, the combination with a work spindle and a stock-feeding mechanism, of a rotary shaft, an arm mounted to oscillate thereon, a stock 120 stop on said arm arranged to be moved thereby into alinement with said spindle, mechanism actuated by said rotary shaft for oscillating said arm, a cam on said rotary shaft, and mechanism actuated by said 125

cam for moving said arm lengthwise of said shaft.

33. In a metal-working machine, the combination with a work spindle and a stock-feeding mechanism, of a rotary shaft, an arm mounted to oscillate thereon, a stock stop on said arm arranged to be moved thereby into alinement with said spindle, mechanism actuated by said rotary shaft for oscillating said arm, a cam on said rotary shaft, a bar telescoping in said shaft and connected with said arm for moving it lengthwise of said shaft, and a projection on said bar for engagement with said cam.

10 34. In a multiple-spindle metal-working machine, a bed comprising a head frame and a tail frame, a spindle-carrying turret mounted in the head frame, a tool slide located between said frames, a feed shaft for the tool slide, a stock stop movable about the axis of the tool slide and also lengthwise of said axis toward and from the turret, a cam in the head frame and located on the feed shaft and associated mechanism for imparting said longitudinal movements to said stock stop, and mechanism actuated by said feed shaft for imparting said rocking movements to said stock stop thereby to move said stop into and out of alinement with one 25 of the spindles on the turret.

35. In a multiple-spindle metal-working machine, a bed comprising a head frame and a tail frame, a spindle-carrying turret mounted in the head frame, a tool slide located between said frames, a feed shaft for the said tool slide, a stock stop movable about the axis of the tool slide and also lengthwise of said axis toward and from the turret, a cam in the head frame and located 30 on the feed shaft and associated mechanism for imparting said longitudinal movements to said stock stop, a cam on said feed shaft and associated mechanism for imparting said rocking movements to said stock stop 40 thereby to move said stop into and out of alinement with one of the spindles on the turret.

36. A multiple-spindle metal-working machine, comprising a plurality of spindles, a 50 turret therefor, a tool slide to receive tools for operation on the work held by said spindles, a feed shaft for reciprocating said slide toward and from said turret, a supplemental tool holder, automatic mechanism for moving said tool holder in a direction parallel with the path of movement of the tool slide but independently thereof, and mechanism for automatically moving said tool holder laterally into and out of potential working 55 relation to the work in one of said spindles.

37. A multiple-spindle metal-working machine, comprising a plurality of spindles, a 60 turret therefor, a tool slide to receive tools for operation on the work held by said spindles, a feed shaft for reciprocating said

slide toward and from said turret, a supplemental tool holder pivoted to move about an axis parallel with the axis of said turret and arranged to move axially, automatic mechanism for rocking said tool holder to potential working position, and mechanism for moving said tool holder axially independently of said tool slide.

38. A multiple-spindle metal-working machine, comprising a plurality of spindles, a 70 turret therefor, a tool slide to receive tools for operation on the work held by said spindles, a feed shaft for reciprocating said slide toward and from said turret, a supplemental tool holder independent of the tool 75 slide and pivoted to move about an axis remote from the turret but parallel with the turret axis, automatic mechanism actuated by the feed shaft for rocking said tool holder into potential working position, and 80 automatic mechanism actuated by the feed shaft for feeding and retracting said tool holder lengthwise of its axis.

39. A multiple-spindle metal-working machine, comprising a plurality of spindles, a 85 turret therefor, a tool slide to receive tools for operation on the work held by said spindles, a feed shaft for reciprocating said slide toward and from said turret, a supplemental tool holder pivoted to move about 90 the axis of the feed shaft, cams on said feed shafts and mechanisms respectively associated therewith for rocking said tool holder to and from working position and 95 axially feeding and retracting said tool holder.

40. A multiple-spindle metal-working machine, comprising a plurality of spindles, a 100 turret therefor, a tool slide to receive tools for operation on the work held by said spindles, a feed shaft for reciprocating said slide toward and from said turret, a supplemental tool holder supported and movable independently of the tool slide, and 105 arranged adjacent the stockfeeding station 110 for the spindles, and automatic mechanisms connected to the feed shaft for moving said tool holder laterally of the turret into potential working position and for feeding and retracting said tool holder lengthwise of the 115 turret axis.

41. In a multiple-spindle metal-working machine, a turret, work spindles carried thereby, a main tool slide, a member pivoted at one end and arranged to have its free end move transversely relatively to one of the spindles, mechanism for actuating said member, and a stock stop and a tool on the free end of said member for alternate engagement with the work presented successively 120 thereto by the spindles.

42. In a multiple-spindle metal-working machine, a turret, work spindles carried thereby, a main tool slide, a member arranged to move transversely relatively to 125

one of the spindles and also longitudinally thereof, a stock stop and a tool carried by said member, automatic mechanism for moving said member laterally first to present the 5 stock stop in operative position and then to present said tool in working position, and mechanism for reciprocating said member longitudinally of said spindle.

43. A multiple-spindle metal-working machine comprising a bed, a turret, a plurality of spindles journaled in bearings in said turret, a source of lubricating oil supply, means for receiving oil dripping from the bearings and conveying it to said source of 10 supply, a pump connected with said oil supply, conduits leading from the pump to the spindle bearings, and power-transmitting connections for operating said pump, in consequence of which oil is drawn from 15 said source and forced to the spindle bearings.

44. A multiple-spindle metal-working machine comprising a supporting structure having a tank or reservoir for lubricating 20 oil, a rotary turret journaled in said structure and provided with a plurality of spindle-bearings, rotary work spindles journaled in said bearings, oil conduits in said turret leading to said bearings, a pump connected 25 with said tank or reservoir and also connected with said conduits, and power-transmitting connections for driving said pump.

45. A multiple-spindle metal-working machine comprising a base having connected 30 lubricating oil receptacles at both ends, a bed having a head frame located over one of said receptacles, and a tail frame located over the other receptacle, a turret journaled in the head frame and provided with spindle bearings and with oil conduits leading to 35 said bearings, spindle-driving power-transmitting mechanism located in the tail frame, an oil pump driven by said power-transmitting mechanism, and connected with the oil 40 receptacle in the tail end of the base, and conduits leading from said pump to the conduits in the turret.

46. A multiple-spindle metal-working machine comprising a supporting structure 45 having an oil receptacle located to receive lubricating oil dropping from the spindle bearings, a rotary turret journaled in said structure and elevated above the oil receptacle, and provided with spindle bearings

and with oil conduits leading to said spindle 55 bearings, and automatic mechanism for circulating lubricating oil from said receptacle through said oil conduits and said bearings.

47. A multiple-spindle metal-working machine comprising a bed, a rotary turret journaled therein and provided with spindle bearings, said turret being provided with a central oil conduit, and with branch conduits leading therefrom to all the spindle 60 bearings, a plurality of work spindles journaled in said bearings, an oil pump having its delivery end connected with said central conduit, and power transmitting mechanism 65 for rotating said spindles and for operating said pump.

48. A multiple-spindle metal-working machine, comprising a base having a receptacle for lubricating oil, a bed provided with a head frame and a tail frame, a rotary turret journaled in the head frame and having an 70 extension journaled in the tail frame, spindle bearings in said turret, work spindles journaled in said bearings, an oil conduit extending through said turret extension and having branch ducts leading to the spindle 75 bearings, spindle-driving mechanism supported by the tail frame, a pump having an inlet connected with said oil receptacle and an outlet connected with said turret, and power-transmitting connections between said 80 pump and said spindle-driving mechanism.

49. A multiple-spindle metal-working machine, comprising a base having a receptacle for lubricating oil, a bed provided with a head frame and a tail frame, a rotary turret 85 journaled in the head frame, an oil conduit concentric with the axis of the turret and extending from the tail frame to the interior of the turret, ducts in the turret leading from said conduit to the spindle bearings, 90 work spindles journaled in said bearings, spindle-driving mechanism supported by the tail frame, a pump at the tail end of the machine and having an inlet communicating with the oil receptacle and an outlet connected with said conduit, and power-transmitting mechanism supported by the tail 95 frame for operating said pump and for driving said spindles.

In testimony whereof I have affixed my signature.

FRANK L. CONE.
